UNITED STATES PATENT OFFICE

116,430

DESIGN FOR A SUIT ENSEMBLE

Max Kolmer, New York, N. Y.

Application June 23, 1939, Serial No. 85,637

Term of patent 3½ years

To all whom it may concern:

Be it known that I, Max Kolmer, a citizen of the United States, and a resident of the city of New York, in the county of New York, and State of New York, have invented a new, original, and ornamental Design for a Suit Ensemble, of which the following is a specification, reference being had to the accompanying drawing, forming a part thereof:

Fig. 1 is a front view of a suit ensemble showing my design.

Fig. 2 is a rear view thereof.

Fig. 3 is a front view of the suit section of the ensemble shown in Fig. 1.

Fig. 4 is a rear view of Fig. 3.

I claim:

The ornamental design for a suit ensemble, substantially as shown.

MAX KOLMER.
